UNITED STATES PATENT OFFICE.

LOYD J. CALDWELL, OF MILLERSBURG, INDIANA.

FEED-GRINDER.

SPECIFICATION forming part of Letters Patent No. 239,600, dated April 5, 1881.

Application filed August 18, 1880. (No model.)

To all whom it may concern:

Be it known that I, LOYD J. CALDWELL, of Millersburg, in the county of Elkhart and State of Indiana, have invented certain new and useful Improvements in Feed-Grinders; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved feed-grinder. Fig. 2 is a plan view, and Fig. 3 is a vertical section of the same.

This invention has reference to improvements in feed-grinding by a reciprocating motion; and it consists of a corrugated four or more sided grinding shaft or blade, with or without angular blades thereon, adapted to fit and operate in a corrugated tube with a hopper with a feeding-gate, which is lifted only (to feed the grain into the grinding-tube) when the grinding-shaft, on its upward stroke, rises into the hopper, substantially as hereinafter more fully set forth.

In the accompanying drawings, A indicates a corrugated four or more sided grinding-shaft, which may also be fitted with angular or oblique blades *a a*. This shaft is reciprocated vertically within a correspondingly-corrugated tube, A'. The lower end of this grinding-shaft is provided with a dish or receptacle, *b*, set at an inclination with the shaft, and having a chute which discharges the ground grain fall-

ing thereon from between the shaft and the tube. The tube A' has attached at its lower end a plate, *c*, with a set-screw, *c'*, to secure that end thereof to the supporting-frame, while its upper end may likewise be fastened in position, as shown.

C is the hopper, suitably supported upon the supporting-piece of the tube A'. This hopper is provided with a feed-gate, B, which lifts only as the upper end of the grinding-shaft rises into the hopper, which permits of the feeding of the grain in the hopper down between, and to be ground by the shaft and the sides of the tube.

The shaft and tube may be triangular in cross-section and adapted to operate together, while their corner-angles form the sides.

Having thus fully described my invention, I claim and desire to secure by Letters Patent of the United States—

In a feed-grinder of the described class, the combination, with the grinding-tube A', having hopper C and vertically-reciprocating corrugated grinding shaft or staff A, of the feed-gate B, placed in the bottom of the hopper around the shaft, and lifted or closed alternately as the shaft rises or sinks in the hopper, as set forth.

In testimony that I claim the foregoing as my own I have hereto affixed my signature in presence of two witnesses.

LOYD JOSEPH CALDWELL.
